UNITED STATES PATENT OFFICE.

FRANK F. HOPKINS, OF SEATTLE, WASHINGTON.

REFUSE-BURNER.

1,276,920.

Specification of Letters Patent. Patented Aug. 27, 1918.

Application filed June 23, 1917. Serial No. 176,478.

To all whom it may concern:

Be it known that I, FRANK F. HOPKINS, a citizen of the United States, and resident of the city of Seattle, county of King, and 5 State of Washington, have invented certain new and useful Improvements in Refuse-Burners, of which the following is a specification.

My invention relates to refuse burners, 10 and particularly of that kind which are employed in the burning of the waste from saw mills and other wood working establishments.

The object of my invention is to build a 15 burner of a design which is cheap to build, which will stand exposure to the elements and to the heat of the fire and one in which the supply of air thereto may be regulated both in accordance with the needs of combustion and for the purpose of supplying cooling protection to the skin or walls of the burner.

It is also my purpose to control the supply 20 of air in such manner that there will be no danger of sparks or brands being blown out of the burner by high winds, while at the same time supplying the fire with a liberal amount of air.

The construction of my invention will be 25 herein described and the features thereof which I deem to be novel and upon which I desire patent protection will be particularly defined by the claims.

In the accompanying drawings I have 30 shown my invention in the forms of construction which I now most prefer to use. I do not, however, consider my invention as limited to the constructions shown, as other shapes and arrangements may be used 40 which will have my invention embodied therein.

Figure 1 is an elevation of a preferred 45 form of construction, a part of the front side being shown as broken away to better illustrate the invention.

Fig. 2 is a detail showing on a larger scale one manner of mounting and adjusting the draft regulating doors.

Fig. 3 is a front view of the means employed in Fig. 2 for holding up the chain.

Fig. 4 is a like view showing a slightly different manner of mounting and adjusting the draft regulating doors.

In the disposal of waste from saw mills 55 and other wood working establishments, an open bon fire has been found to be effective,

and such is the means employed at many small mills. Such practice is, however, dangerous in the great liability of scattering fire by winds and spread of fire through wood 60 waste which becomes scattered outside the usual limits of the fire. It is the usual practice to provide some form of incinerator or burner.

The burner which is the subject of this invention is, in principle, only a cover placed over an open bon fire and provided with means for regulating the supply of air to the fire. I do not consider it necessary to provide any flues or grates beneath the fire 65 bed. I simply erect whatever shape of inclosing structure best suits the situation and the requirements, the cost thereof being considered as an important factor.

A type of inclosing structure which will 70 excellently fit most conditions, including that of first cost and after maintenance, is a conical structure employing post or rib members 1 and a skin composed of metal sheets 2. This is provided with an elevated 75 opening at one side through which a chute 3 at the end of a conveyer 4, projects, so that the refuse is discharged approximately at the center of the burner.

Extending about the bottom of the burner 80 is a zone which is lacking a permanently secured skin, but which is provided with doors or dampers which may be adjusted to control this space and the entrance of air therethrough.

This control may be secured in a variety 85 of ways. I now prefer to do this by providing, for each of the spaces between adjacent posts 1, a door, 5, hinged to be opened or closed. This hinging is either by a pivot 90 50 at the upper edge of the door, as shown in Figs. 1 and 2, or by a pivot 51 at its lower edge, as shown in Fig. 4.

When hinged at their upper edges, the opening of these doors may be conveniently 100 and effectively controlled by chains 6, which may be held to sustain the door at any elevation, by engaging any securing means carried by the frame, as by a slotted plate 60.

When hinged at their bottom edges the 105 doors may be controlled and held in adjusted position by bars 61 which are hinged to the upper edges of the doors and have their upper ends bent laterally to enter any one of a series of holes 62 in the several 110 posts 2.

By the use and proper adjustment of the

means described, the amount of air supplied to the fire and the side from which it comes may be fully controlled. The effect of the wind may be neutralized or used as desired.

5 When it is desired to check combustion and hold the fire, this may be done by closing all the draft doors.

I have found that a burner constructed along these lines is efficient and capable of 10 destroying a large amount of refuse and yet the walls do not become objectionably heated. It may be constructed of light weight material and thus cost but little. The skin may be of thin metal, as No. 16 gage. Being 15 thin it quickly radiates the heat received from the fire and does not quickly burn out. It is to be noted that by virtue of the provision of a completely open zone entirely around the base of the structure it is possible to 20 admit a current of air which will contact with every part of the surface of the burner and this largely aids in preventing the thin shell from becoming so highly heated as to be quickly burnt out and destroyed. The 25 burner is cheap in cost and if burnt out may be quickly and cheaply replaced.

The air being admitted at the bottom and sweeping along approximately horizontally, aids in promoting complete and rapid combustion.

The upper opening of the burner would preferably be provided with a screen or spark arrester, as 7.

What I claim as my invention is:

1. A refuse burner comprising a hollow 35 conoidal structure having upright posts and a skin supported by these posts, the lower edge of said skin being raised to form a bottom draft zone, and doors each hinged along a horizontal edge, and controlling the section of the draft zone between adjacent posts, and means for adjustably controlling the opening of said doors, said doors being conjointly of such size as to completely open or close the draft zone. 40

2. A refuse burner comprising a plurality of posts, and a skin supported thereby comprising a plurality of overlapped plates the lowermost of which has its lower edge spaced from the ground to form a continuous open draft zone and doors having pivots at their horizontal edges which pivots are engaged with the posts, said doors being conjointly of such size as to completely open or close said draft zone and means for holding said doors in adjusted position. 45

Signed at Seattle, Washington, this 12th day of June, 1917.

FRANK F. HOPKINS.
